Patented June 28, 1921.

UNITED STATES PATENT OFFICE.

ROBERT L. JORDAN, OF CHICAGO, ILLINOIS.

INTERLOCKING BRAKE-SHOE.

1,382,785.

Specification of Letters Patent. Patented June 28, 1921.

Application filed May 5, 1920. Serial No. 379,169.

To all whom it may concern:

Be it known that I, ROBERT L. JORDAN, a citizen of the United States, residing at Chicago, in the county of Cook and State of Illinois, have invented certain new and useful Improvements in Interlocking Brake-Shoes, of which the following is a specification.

This invention relates to improvements in railway brake shoes, and has reference more especially to that type of brake shoe which is adapted to have attached to the face or wearing portion thereof a back or rear portion of a partially worn brake shoe, so that such partially worn shoes, instead of being scrapped as at present, may be entirely used up by applying them to new brake shoes. This type of brake shoe is commonly known as an interlocking shoe.

Various constructions of interlocking brake shoes designed to save most of the waste or scrap of ordinary shoes and to effect an economy of metal have heretofore been proposed, but the chief objection heretofore existing in shoes of this type has resided in the fact that the partially worn shoe, when worn down very thin, breaks in two, and fragments thereof fall away, being liable to lodge in frogs or switches and cause trouble, in addition to sometimes destroying the smooth wearing face of the shoe structure which remains on the brake head.

Another objection, which has heretofore inhered in many interlocking shoes, resides in their unduly complicating structure, making them impractical on the score of expensive cost of production.

With these faults in view, I have devised the interlocking brake shoe of the present invention, one object of the latter being to provide an interlocking shoe of such a construction that the worn shoe may be practically entirely used up, without leaving fragments or chips of any substantial size, such as might cause possible mischief from falling onto the track. Another object is to provide an interlocking shoe having means for attaching the worn shoe to the new shoe so securely as to prevent any danger of its becoming detached in service. This object is attained chiefly by the provision of a novel attaching or securing key which itself is locked in place by the same key which attaches the new shoe to the brake head. Still another object is to provide a brake shoe of great strength to resist breaking strains, this

object being attained by the use of a novel malleable metal insert.

Other objects and advantages of the invention will be apparent to those skilled in the art from the following detailed description, when taken in connection with the accompanying drawing in which I have illustrated one practical embodiment of the novel structural features of the invention, and in which—

Figure 1 is a central longitudinal section of a complete assembly comprising a brake head, a new shoe attached to the brake head, and a partially worn shoe or slipper attached to the wearing face of the new shoe;

Fig. 2 is a bottom plan view of Fig. 1, with the transverse locking key omitted;

Fig. 3 is a vertical transverse section taken on the line 3—3 of Fig. 1;

Fig. 4 is a transverse section taken on the staggered line 4—4 of Fig. 2;

Fig. 5 is a side elevation, partly in section, of the malleable insert; and,

Fig. 6 is an elevation of the transverse locking key by which the worn shoe or slipper is secured to the face of the new shoe.

Referring to the drawings, 10 designates the brake head which is of the well known standard construction, and need not be particularly described. 11 designates, as an entirety, the body of the shoe itself which, in the preferred embodiment of the invention, includes a malleable iron insert which is shown in side elevation in Fig. 5 and is preferably of the full thickness of the shoe, the insert also having formed integral therewith the usual central attaching lug. First describing the malleable insert, the same comprises a central bridge plate 12 from which rises the central attaching lug 13 formed with the usual aperture 14 for the passage of the main fastening key 15 of the brake head, and spiral, generally S-shaped, extensions 16 (Fig. 2) extending from the opposite ends of the bridge plate 12 toward the outer ends of the shoe, and thin stiffening strips 17 and 18 connecting and bracing the inner and outer limbs of the S-shaped members in the region closely adjacent to the back of the shoe.

Around this malleable insert is cast the gray iron body 19 having, in general, the structural form of a standard shoe and provided at the opposite ends of its back with the usual concave guide lugs 20 for the forked ends of the brake head 10, and trans-

verse abutment lugs 21 for the ends of the brake head. Centrally of the face of the shoe, however, is a socket 22 into which fits the central attachment lug 13 of the worn shoe. The bottom wall of this socket, which is constituted by the central plate 12 of the insert, is formed with a central transverse slot 23, and in register therewith is a transverse slot 24 formed through the central attachment lug 13. At the opposite ends of the slot 23 are shoulders 25.

At the opposite ends of the wearing face of the shoe body are formed transverse notches 26 to receive the transverse lugs 21 of a worn shoe, and also sockets 27 inwardly of the notches 26 to fit the guide lugs 20 of the worn shoe; these interfitting lugs and sockets acting to resist endwise displacement of the worn shoe from the new shoe under the frictional drag of the worn shoe on the wheel.

28 designates, as an entirety, a locking key that extends through the transverse slots 23 and 24 of the two internested shoes in the manner clearly shown in Figs. 1 and 3. This key is provided with an aperture 29 through which passes the brake head key 15, thereby locking it in place; and on the lower end of the key 28 are lateral ears or lugs 30 that abut squarely against the shoulders 25 of the worn shoe, in the manner most clearly shown in Fig. 3, whereby the worn shoe is locked against separation from the new shoe so long as the lugs 30 remain effective; and since the shoulders 25 are in or above the plane of the back wall of the shoe, it follows that the body of the worn shoe will be completely ground off by the time its locking means has been destroyed or rendered useless. Hence, in the actual use of the device, the only chips that result are those represented by the guide lugs 26 and 27, which are so small as to represent negligible waste not likely to cause injury by falling to the track.

In the practical use of the invention, a new shoe is first applied to the brake head, and when the same is worn down to one-half or one-third its original thickness, it is removed and applied to the face of a new shoe, the two being then applied to the brake head, resulting in the combined interlocking structure illustrated in Fig. 1. This structure is then used until the worn shoe has been used up and the second new shoe has worn away to a point at which it is too thin for further use alone, whereupon it is removed and then applied to the face of a third new shoe, and so on.

I am aware that it has heretofore been proposed to attach a worn shoe to a new shoe by means of central transverse key lugs on each of two shoes which have a spring locking engagement with each other. Such a connection, however, is uncertain and un-

reliable because of depending upon the elastic engagement of the two lugs with each other to fasten the worn shoe onto the new shoe. It will be observed that my construction employs a single or one-piece key by which the worn shoe is held locked to the new shoe until the worn shoe is entirely worn away, and this one-piece key can itself be locked in place by the ordinary brake head fastening key.

75

I claim—

1. An interlocking brake shoe, comprising a new shoe having a central apertured attachment lug on its back for attachment to a brake head, and a central socket in its face shaped to receive a like central attachment lug of a worn shoe, a partially worn shoe fitted to the face of said new shoe, and a one-piece locking key passed through both attachment lugs and secured by the brake head fastening key.

2. An interlocking brake shoe, comprising a new shoe having a central apertured attachment lug on its back for attachment to a brake head, and a central socket in its face shaped to receive a like central attachment lug of a worn shoe, both of said attachment lugs being transversely slotted, and a one-piece locking key passed through the transverse slots of said attachment lugs and having an aperture in register with the aperture of the outer attachment lug and adapted to be entered by the brake head fastening key.

3. An interlocking brake shoe, comprising a new shoe having a central apertured attachment lug on its back for attachment to a brake head, and a central socket in its face shaped to receive a like central attachment lug of a worn shoe, said attachment lugs being transversely slotted and formed with abutment shoulders at opposite sides of the lower end of the slot, and a locking key passed through the transverse slots of said keeper lugs, said locking key having at its lower end abutment lugs engaged with said shoulders and having an aperture in its upper end in register with the aperture of the outer keeper lug and adapted to be entered by the brake head fastening key.

4. A brake shoe having a malleable insert extending throughout the major portion of the length of the shoe, and said insert including a central apertured attachment lug on the back of the shoe.

115

5. A brake shoe having a malleable insert comprising a central bridge plate and curved extensions leading from the ends of said bridge plate toward the ends of the shoe, and a central apertured attachment lug on the back of the shoe integral with said bridge plate.

120

6. A brake shoe having a malleable insert comprising a central bridge plate of less thickness than the shoe body and disposed

130

in the back region of the latter, S-shaped extensions leading from the ends of said bridge plate toward the ends of the shoe and of the full thickness of the latter, and a 5 central apertured attachment lug on the back of the shoe integral with said bridge plate.

7. A brake shoe having a malleable insert comprising a central bridge plate of less 10 thickness than the shoe body and disposed in the back region of the latter, S-shaped extensions leading from the ends of said bridge plate toward the ends of the shoe and of the full thickness of the latter, 15 stiffening strips connecting and bracing the inner and outer limbs of said S-shaped extensions in the region adjacent to the back

of the shoe, and a central apertured attachment lug on the back of the shoe integral with said bridge plate. 20

8. In an interlocking brake shoe, a shoe having a central apertured attachment lug on its back for attachment to a brake head, and a central socket in its face shaped to receive a like central attachment lug of a 25 worn shoe, said attachment lug having a transverse slot, in combination with a locking key engageable with said slot, said locking key having lateral lugs on its inner end for engagement with the worn shoe, and an 30 aperture at its outer end adapted to be entered by a brake head fastening key.

ROBERT L. JORDAN.
